(No Model.)

T. O. McMURTRAY.
CAR COUPLING.

No. 398,844.

Patented Mar. 5, 1889.

UNITED STATES PATENT OFFICE.

THOMAS O. McMURTRAY, OF YAZOO, MISSISSIPPI.

CAR-COUPING.

SPECIFICATION forming part of Letters Patent No. 398,844, dated March 5, 1889.

Application filed May 26, 1888. Serial No. 275,246. (No model.)

To all whom it may concern:

Be it known that I, THOMAS O. McMURTRAY, a citizen of the United States, residing at Yazoo city, in the county of Yazoo and State 5 of Mississippi, have invented a new and valuable Car-Coupling Machine, of which the following is a specification.

My invention relates to car-couplings; and it consists in certain improvements in the construction of the same, as hereinafter described and claimed.

In the accompanying drawings, Figure 1 is a central vertical longitudinal section of my improved car-coupling. Fig. 2 is a side view 15 of the same. Fig. 3 is a plan view of the same. Fig. 4 illustrates the coupling-pin and a detent pivoted thereto.

A designates a draw-head, which is slotted and formed with interior inclined surfaces, as 20 shown, to receive and permit the movement of a coupling-pin and weighted slide, as herein-after set forth.

G indicates an elevator-block, which is placed on the top of the draw-head, and is 25 perforated to receive the coupling-pin and slotted to receive a weighted slide, B. The block G rests over the central slot in the draw-head, and is connected with the draw-head by arms F. The said arms F are pivotally connected with the forward part of said block by 30 a bolt, f, and extend downward and rearward to the projections K on the sides of the draw-head, where they are pivotally secured to the draw-head by a bolt, f', as shown in the drawings.

35 The projections K forming bearing-surfaces for the ends of the arms F. The said block G is further connected with the draw-head by means of the arms E, the forward ends of said arms being connected by a bolt, e, with lugs on block G at its rear end, and the rear ends of said arms being connected 40 with lugs on the draw-head by bolts e'.

The coupling-pin C passes through an aperture in block G and through the slotted draw-head, as shown. The weighted slide B is made substantially in the form shown, with an inclined edge in its lower part, so that when the parts of the coupling are in the position shown in Fig. 1 and the link D is drawn the 50 slide will be raised, as indicated in dotted lines. The forward lower part of the slide closes against the coupling-pin C. The slide

B is hung to the block G by a pin or bolt, b, and extends down through the slot in said block into the draw-head.

J indicates the stop or check lug, which is secured to the top of the draw-head at its rear end, and is provided with a spring, H, which is made fast in position in front of the check-lug.

When the block G and slide B are resting in position as seen in Fig. 1, and the link D is pressed against the coupling-pin C, the said block and slide are immediately raised on the pivoted arms E and F, which approach a vertical position, thus allowing the link to enter the draw-head, and the block and slide, moving rearward, come in contact with spring H and lug J, and are pushed forward and return to their former position, the coupling of 65 cars being thus automatically effected.

The head of the coupling-pin C has pivoted thereto a hook or detent, L, which in its normal position connects with a catch, l, on the block G, as shown in Fig. 1, and prevents the 75 coupling-pin from being forced upward by the slide B, when the latter is raised, by the link D pressing against the inclined edge thereof.

A branching chain, M, for use in uncoupling, is connected with slide B and pin C, a short chain being connected with the detent L, so that when the chain M is drawn the detent will be raised before the pin is drawn upward.

I claim—

1. The combination, with the draw-head, of a block resting thereon, a coupling-pin passing vertically through said block and draw-head, and oblique arms having their ends pivoted, respectively, to said block and draw-head, whereby the coupling-pin may be withdrawn independently of the block or by raising the arms, substantially as described.

2. The combination, with the slotted draw-head, of a coupling-pin, a slotted movable block mounted on the draw-head, a weighted slide capable of independent bodily vertical movement in said block, and a series of arms connected with said block and with the draw-head, substantially as and for the purposes described.

3. In combination with the draw-head, a movable block, G, a coupling-pin, and a

weighted slide carried by said block, pivoted arms connected with the block and with the draw-head, and a stop or check lug, J, provided with a spring, said lug being in position 5 to stop the movement of the said block on said pivoted arms, substantially as set forth.

4. The combination of a movable block, G, mounted on the draw-head, and a coupling-pin carried by said block, a detent, L, pivot-

ally connected with the coupling-pin, and to adapted to connect with a catch, l, with which said block is provided, substantially as set forth and described.

THOMAS O. McMURTRAY.
